(57) **CLAIM**

The ornamental design for a popcorn maker assembly, as
shown and described.

DESCRIPTION

FIG. 1 is a exploded perspective view of a popcorn maker
assembly, illustrating a cover, an insert, and a bowl;

FIG. 2 is a second perspective view of the popcorn maker
assembly;

FIG. 3 is a right side elevational view of the popcorn maker
assembly, illustrated in FIG. 2;

FIG. 4 is a bottom plan view of the popcorn maker assembly,
illustrated in FIG. 2;

FIG. 5 is a top plan view of the popcorn maker assembly,
illustrated in FIG. 2;

FIG. 6 is a right side exploded view of the popcorn maker
assembly, illustrated in FIG. 2;

FIG. 7 is a rear elevational view of the popcorn maker assem-
bly, illustrated in FIG. 2;

FIG. 8 is a front elevational view of the popcorn maker assem-
bly, illustrated in FIG. 2;

FIG. 9 is a cross-sectional view of the popcorn maker assem-
bly taken along line 9-9 of FIG. 5;

FIG. 10 is a rear elevational view of the insert of the popcorn
maker assembly shown independent of the assembly for ease
of illustration;

FIG. 11 is a front elevational view of the insert shown inde-
pendent of the assembly for ease of illustration;

FIG. 12 is a top plan view of the insert shown independent of
the assembly for ease of illustration;

FIG. 13 is a bottom plan view of the insert shown independent
of the assembly for ease of illustration; and,

FIG. 14 is a left side elevational view of the insert shown
independent of the assembly for ease of illustration.

The characteristic features of the design reside in the non-
concentric container portion of the bowl and the distinct
curved portion on the outside flange of the bowl. The design-
ations of the views below as top, right side, front, and rear are
for ease of discussion only and are not intended to limit the
popcorn maker assembly to one particular orientation. The
popcorn maker assembly can be oriented in other directions
which would alter these designations. The drawings illus-
trated in FIGS. 1-14 are not necessarily drawn to the same
scale, and any change in scale between different views is not
intended to limit the popcorn maker assembly to a particular
size. The cover of the popcorn maker assembly is transparent
or semi-transparent. A left side elevational view of the pop-
corn maker assembly is not included as the left side eleva-
tional view is a mirror image of its respective right side
elevational view.
